UNITED STATES PATENT OFFICE.

GEORGE W. CARTER, OF HAVERHILL, MASSACHUSETTS, ASSIGNOR, BY MESNE ASSIGNMENTS,
TO UNITED SHOE MACHINERY COMPANY, A CORPORATION OF NEW JERSEY.

LASTING-MACHINE.

No. 893,440.

Specification of Letters Patent.

Patented July 14, 1908.

Application filed April 3, 1899. Serial No. 711,477.

To all whom it may concern:

Be it known that I, GEORGE W. CARTER, a citizen of the United States of America, residing at Haverhill, in the county of Essex and Commonwealth of Massachusetts, have invented certain Improvements in Lasting-Machines, of which the following, read in connection with the accompanying drawings, is a specification.

10 This invention relates to machines for use in the manufacture of boots and shoes and more particularly to machines adapted to be employed in conforming an upper to a last.

An object of this invention is to provide 15 means by which the portion of the upper material that is turned over upon the bottom of the shoe may be conformed to the shape of the last and made ready for the reception of the outersole better and more rapidly than 20 has heretofore been done.

To this end a broad feature of this invention consists in providing means for pounding down the shoe stock on the bottom of a last to compact the upper materials against 25 the innersole and to flatten down the wrinkles or folds which are especially prominent at the toe and heel of the shoe. In the embodiment herein shown a pounder is operatively connected with actuating mechanism 30 by which it is moved over the shoe bottom inwardly from the edge of the shoe and downwardly toward or against the shoe bottom. In the machine illustrated the pounding tool advances over the shoe bottom in 35 rubbing contact with the upper so that it forces it inwardly from the edge of the shoe to and beyond the usual tacking line and is then actuated downwardly at an angle to its inward movement for flattening the upper 40 against the innersole.

Another very important feature of this invention consists in the combination of means for working the upper over the last with means for pounding the overworked upper. 45 In the embodiment of the invention shown herein the pounding means is applied to a lasting machine of the type shown in United States Letters Patent No. 584,744 and operates in time relation with means for pulling 50 the upper and crimping it at times to conform it to the last and with means for securing the upper, all of which may be the same as the means shown for the same purposes in said Letters Patent.

Important features of the invention are 55 also found in the combination of grippers for pulling and overlaying the upper with means for pounding the upper and in the combination of the pounding means with means for driving fastenings to secure the 60 upper. The illustrated machine performs the lasting and pounding operation step by step by repeated operations upon successive portions of the shoe.

These and other features of the invention, 65 including certain combinations of parts and details of construction, will be explained in the following description of the machine and will be pointed out in the claims.

Of the drawings, Figure 1 is an elevation 70 showing one side of the machine embodying this invention; Fig. 2 is a perspective showing detail referred to hereinafter. Fig. 3 is an elevation, partly in section, showing operative parts of the machine, including this invention. Fig. 4 is a view similar to Fig. 3, showing the parts in different positions of operation. Fig. 5 is an elevation of a section on line 5 of Fig. 3. Fig. 6 is a plan of 75 the pounder member detached. Fig. 7 is a 80 perspective showing a modified form of the pounder and a section of the actuating member. Fig. 8 is a plan of the pounder shown in Fig. 7. Fig. 9 is an elevation of a section on line 9 of Fig. 8. Fig. 10 is a side elevation 85 of the pounder shown in Fig. 8.

It may be here remarked that the machine comprises a single pair of pincers and actuating connections (for more specific description whereof see United States Patent 584,744) 90 whereby the pincers are made to grasp and strain the upper over the innersole, the lasting operation being carried out as a whole by repeated operations of the pincers applied to different parts of the upper at different times. 95 After the section of upper is overlaid upon the innersole it requires to be fastened thereto and in this connection is employed a tack-holder, shown in the present instance as comprising the members 2, 3, shown detached in 100 Fig. 2, which are journaled in the pounder member 4, for closing together directly below the tack receiving channel 5. Springs 6 operate for normally holding the members in closed position, thereby stopping downward 105 progress of tack 7, and yield for passage of the tack between said members in the driving operation. For a further description of

said parts reference may be had to United States Patent 584,744. The tack, it will be understood, requires to be carried in said holder from the point where it is discharged into the holder to the driving point, and to this end the pounder member 4, wherein the holder is constructed, has connection with part 8 whereto movement forwardly and backwardly is given by actuating mechanism more fully shown and described in United States Patent above referred to. Connected with the member 4 is a smoothly polished part 9, which in the forward movement of said part bears upon and wipes over the upper drawing and holding it in place for the tack driving operation.

Driving of the tack is effected by means of a hammer-rod 10 carried by a bar 14 which is connected by means of a link 15 to suitable actuating mechanism. The actuating mechanism herein shown is like that described in United States Patent No. 441,482, and comprises a torsional spring rod 20 mounted in a tubular casing 21 carried by the frame, said rod being fastened at one end to the casing and carrying at its other end an arm which is connected to the link 15. The bar 14 is lifted against the tension of the spring-rod 20 by means of a cam, and when said cam moves out of engagement with said bar the spring rod 20 operates to depress said bar to drive a tack. Under the arrangement of the present machine the work of pounding and flattening the upper is carried on simultaneously with the tack driving operation. To this end the pounder block or member 4 has its rear end pivotally connected with the part 8, thereby adapting its foremost end for movement downwardly, and the bar 14 which carries the hammer-rod 10 is positioned so that, in descending to drive the tack, and just before reaching the limit of its throw downwardly, it will strike upon the pounder member 4 and drive it downwardly upon the overturned material located thereunder whereby the said material from the edge of the shoe bottom to a point beyond the tacking line is set, and ribs or folds therein, if any, are crushed and flattened down upon the innersole and the surface for receiving the outer-sole is thereby made more uniformly smooth, thus dispensing with or rendering less essential the operation of subsequently pounding down or trimming off the ridge that is formed by these folds. The pounder member 4 is formed with a cam lift 16, which, in the backward movement thereof from over the shoe bottom, will engage the end of the shoe-edge resting member 18 of the machine and lift the pounder member to the altitude required for its next movement forwardly over the shoe bottom. For a full description of the said shoe-edge resting member see United States Letters Patent No. 562,119.

In Figs. 7, 8, 9, and 10 of the drawings I have illustrated a modified construction embodying this invention wherein the bar 40, which is arranged for fixed support on the machine part 8, has, in its foremost end, a socket or chamber for receiving the pounder-member 42, which member 42 comprises the before described tack-holding arrangements (see Fig. 9) and is capable of movement vertically in the said socket or chamber. It also has the incline or cam lift 44 to engage the shoe-edge resting member of the machine, whereby said member 42 is lifted preparatory for the movement forwardly over the shoe and is positioned for engagement with the descending hammer-bar 14, whereby to be driven downwardly upon the overturned upper material located thereunder, all substantially as described before.

In the foregoing description and in some of the claims the term "pounder" is employed as the name for the tool that is used to operate upon the shoe stock for forcing it into position upon the shoe bottom. The term is used for convenience as a name for the tool without any intention of implying thereby any limitation as to the nature of the tool.

Having explained the nature of the invention and fully described a construction embodying the same, I claim as new and desire to secure by Letters Patent of the United States:

1. In a lasting machine, a movable pounder, means to set the pounder in operative position, and means to actuate the pounder to flatten the overturned upper material upon the inner-sole.

2. In a lasting machine, a movable reciprocating pounder, means for setting said pounder in operative position, independent means for forcing the pounder against the overturned upper to flatten the overturned upper material upon the innersole, and means for automatically raising the pounder into position preparatory for a repetition of the operation.

3. A lasting machine comprising a pounder member, and means for imparting to said member a movement into and out of engagement with the shoe which causes it to bear upon and wipe over the upper, in combination with mechanism which operates to drive the pounder against the upper to flatten the latter upon the inner-sole.

4. A lasting machine comprising a pounder having a movement which causes it to bear upon and wipe over the upper in combination with tack driving mechanism which operates to drive the pounder against the upper to flatten it and also drives the tacks which hold the upper to the inner-sole.

5. A lasting machine comprising a pounder having a movement which causes it to bear upon and wipe over the upper in combina-

- tion with tack driving mechanism which operates to drive the pounder against the upper to flatten it and also drives the tacks which hold the upper to the inner-sole, and 5 tack holding members carried by the pounder.

6. A lasting machine comprising a pounder member having a movement which causes it to bear upon and wipe over the upper, in combination with driving mechanism which 10 operates to drive the pounder against the upper to flatten the latter upon the inner-sole, and a cam lift to raise the pounder to its former position in readiness for a repetition of the operation.

15 7. A lasting machine comprising means for overlaying the upper upon the inner-sole and means for securing the sections of overturned upper to the inner-sole, combined with a pounder, and means for actuating it to pound the overturned upper upon the inner-sole, the relative arrangement of the mechanism causing the pounding operation 20 to take place simultaneously with the operation for securing the upper to the inner-sole.

25 8. In a machine for working uppers over a last, a pounder and means to actuate it over the shoe bottom, combined with separate means to actuate it toward the shoe bottom after its inward movement to flatten the upper material upon the innersole.

30 9. In a machine for working uppers over a last, a pounder, means for setting it in operative position and spring - actuated means for moving the pounder against the 35 overturned upper material to flatten and set the upper material upon the innersole.

35 10. In a lasting machine, means for driving a fastening to secure an overturned upper to an innersole, and means for pounding 40 down the overturned upper material to flatten it upon the innersole, said pounding means being operated near the end of movement of the fastening driving means.

45 11. A lasting machine, comprising means for progressively overlaying successive portions of the edge of an upper upon an innersole, means for pounding the overlaid upper to flatten it down upon the innersole, and means for securing said upper to the inner-sole after the overlaying operation.

50 12. A lasting machine, comprising means for stretching, plaiting, and overlaying the edge of an upper upon an innersole, a pounder and means for actuating said pounder to flatten 55 down the plaited portions of the upper upon the innersole.

55 13. In a lasting machine, gripper for working an upper over a last, mechanism for actuating the grippers to plait the upper, and means for pounding the plaited upper to flatten it down upon the innersole.

60 14. In a lasting machine, gripper mechanism for actuating the grippers to work successive portions of an upper over a last 65 progressively, mechanism for securing the

overworked upper, and means for pounding the overworked upper during the securing operation to flatten the upper.

15. In a machine of the class described, the combination with a pounder, of automatic mechanism including a yielding element for actuating the pounder over the work and for actuating the pounder toward the surface of the work.

16. In a machine of the class described, 70 the combination with means for working successive portions of an upper over a last, of means for pounding said portions of the upper in a direction substantially perpendicular to the last bottom to set them in overworked position.

17. In a machine of the class described, 75 the combination with means for working an upper over a last, of means for simultaneously securing the upper to an innersole and pounding the upper to flatten it against the innersole.

18. In a machine arranged to permit a shoe to be fed with relation to the devices operating thereon, the combination with a 80 pounding device, of automatic means for actuating the pounding device downwardly and yieldingly toward and upwardly away from the shoe for engaging and disengaging the upper to flatten successive portions of the upper on the bottom of a shoe against the innersole.

19. In a machine of the class described, 85 means for straining a portion of an upper over the bottom of a last, and yieldingly actuated means following the operation of the straining means automatically for pounding the strained portion of the upper to flatten it.

20. In a machine of the class described, 90 means for straining a portion of an upper to work it over a last, means for holding the strained portion of the upper, and means following the operation of the straining means automatically and having provision 95 for imparting a yielding blow for pounding said portion of upper against the inner-sole to set it in overworked position.

21. In a machine of the class described, 100 the combination with a pounding device, of means to actuate said device in substantially the plane of a last bottom for laying the upper material over the bottom of the last, and means for actuating said pounding device toward the last bottom for flattening the upper material against the bottom of the last.

22. In a machine of the class described, 105 pounding means, a carrier therefor, means for actuating the carrier and the pounding means in substantially the plane of the shoe bottom, and means for actuating the pounding means at an angle to the direction of 110 said first movement for flattening an upper against the shoe bottom.

115

120

125

130

23. In a machine for conforming the marginal portion of an upper to a last, the combination with a pounder, of mechanisms for actuating the pounder inwardly over the 5 surface of the upper and then downwardly toward the upper.
24. In a machine for conforming the marginal portion of a shoe upper to a last, the combination with a pounder, of mechanisms 10 for actuating the pounder inwardly over the shoe bottom to and beyond the tacking line and downwardly to force the upper against the innersole, and a rest for the side of the shoe.
- 15 25. In a machine for conforming the marginal portion of a shoe upper to a last, the combination with a device having a movement from and toward the shoe to force the upper inwardly from the edge of the inner 20 sole, of means for actuating said device downwardly by impact to pound the upper against the innersole, and means for securing the upper in position.
26. In a machine for conforming the marginal portion of a shoe upper to a last, the combination with a pounder arranged to force the upper inwardly away from the edge of the innersole and downwardly against the innersole beyond the tacking line, of devices 30 for actuating the pounder, and mechanism constructed and arranged to be operated while the pounder is in operation for driving tacks to fasten the upper in the position to which it is forced by the pounder.
- 35 27. In a machine for conforming the marginal portion of a shoe upper to a last, the combination with a member having a recess and arranged to extend over the shoe bottom from the edge of the shoe to and beyond the 40 tacking line for forcing the upper inwardly away from the edge of the innersole and downwardly against the innersole, of devices for actuating said member to pound the upper, and means constructed and arranged 45 to insert tacks through the recess in the pounder for securing the upper in the position to which it has been forced.
28. In a machine of the class described, the combination with a carrier, of a pounder 50 for forcing the upper against the innersole, means for actuating the carrier over the shoe bottom, and means for actuating the pounder in its carrier.
- 55 29. In a machine of the class described, the combination with a carrier, of a pounder for forcing the upper against the innersole, means for actuating the carrier over the shoe bottom, and means for actuating the pounder 60 relatively to the carrier at an angle to the direction of its movement with the carrier.
30. In a machine of the class described, a pounder movable to force the upper inwardly from the edge of the innersole and downwardly toward the innersole, a carrier 65 for the pounder, means for actuating the car-
- rier and pounder together to effect one of said movements of the upper, and means for actuating the pounder relatively to the carrier to effect the other movement of the upper.
- 70 31. In a machine of the class described, the combination with a carrier, of means for actuating the carrier over the shoe bottom, a member mounted in the carrier and having provision for supporting a tack, means for driving the tack and means for actuating said member transversely of the carrier to flatten the stock on the shoe bottom.
32. A machine of the class described having the following instrumentalities arranged 80 to operate in time relation; means for forcing the upper inwardly over the innersole, yieldingly actuated means for pounding the upper downwardly against the innersole, and means for fastening the upper.
- 85 33. In a machine of the class described, means for pulling the upper material about the last, means for forcing the upper material inwardly over the bottom of the last, means for tacking the upper material, and means 90 constructed and arranged to extend from the edge of the last to a point beyond the tacking line for pounding the upper downwardly upon the last bottom.
- 95 34. In a machine of the class described, the combination with an upper engaging member, of means for moving said member in substantially the plane of a shoe bottom to force the upper over the edge of the last 100 into position to be secured to the innersole, and means for actuating said member at an angle to the shoe bottom to compact the upper material.
- 105 35. In a machine of the class described, the combination with an upper engaging member, of means for moving said member in substantially the plane of a shoe bottom to force the upper over the edge of the last 110 into position to be secured to the innersole, means to drive a tack from said member, and means to actuate the member substantially perpendicularly to the shoe bottom to compact the upper materials around the tack.
- 115 36. In a machine of the class described, the combination with grippers for pulling an upper over a last, and an upper engaging member, of means for moving said member in substantially the plane of a shoe bottom to force the upper over the edge of the last 120 into position to be secured to the innersole, and means for actuating said member at an angle to the shoe bottom to compact the upper material.
- 125 37. In a machine of the class described, the combination with an upper engaging member, of means for moving said member in substantially the plane of a shoe bottom to force the upper over the edge of a last into 130 position to be secured to the innersole, means to drive a tack from said member, and means

- to actuate the member at an angle to the shoe bottom to compact the upper materials around the tack simultaneously with the insertion of the tack.
- 5 38. In a machine of the class described, the combination with a reciprocating tack block movable over the shoe bottom, of a driver for inserting a tack from the block, and an abutment moving with the driver and 10 constructed and arranged to actuate the tack block downwardly to compact the stock around the tack during the insertion of the tack.
- 15 39. In a machine of the class described, the combination with a reciprocating tack block movable over the shoe bottom, of a driver for inserting a tack from the block, an abutment moving with the driver and constructed and arranged to actuate the tack 20 block downwardly to compact the stock around the tack during the insertion of the tack, and means for raising the tack block from the shoe bottom.
- 25 40. In a machine of the class described, the combination with a reciprocating tack block movable over the shoe bottom, of a driver for inserting a tack from the block, and an abutment moving with the driver and constructed and arranged to actuate the tack 30 block downwardly to compact the stock around the tack during the insertion of the tack, said block being formed with an incline on its lower face, and means to be engaged by said incline to raise the tack block during 35 the movement of the block backwardly away from the shoe.
41. In a machine of the class described, the combination with means for pulling an upper over a last, and a reciprocating tack 40 block movable over the shoe bottom, of a driver for inserting a tack from the block and an abutment moving with the driver and constructed and arranged to actuate the tack block downwardly to compact the stock 45 around the tack during the insertion of the tack.
42. In a machine of the class described, the combination with a pounder, of automatically operating means for actuating the 50 pounder inwardly and outwardly over the work, and means for actuating the pounder downwardly against the work between the inward and outward movements thereof.
43. In a machine of the class described, the combination with a pounder, of separate 55 means operating automatically for imparting to the pounder a movement inwardly over the work in rubbing contact therewith and a movement downwardly at an angle to the first mentioned movement.
44. In a machine of the class described, the combination with a pounder of automatically operating means for actuating the 60 pounder inwardly and outwardly over the surface of the work, means for imparting to the pounder a momentary downward impulse between the inward and outward movements, and means for raising the pounder during its outward movement.
45. In a machine for conforming the marginal portion of a shoe upper to a last, a carrier adapted for movement inwardly and outwardly over a shoe bottom to wipe the upper toward lasted position, a block movably mounted in said carrier, and means operating automatically for actuating the block downwardly in said carrier between the inward and outward movements of the carrier. 70
46. In a machine for conforming the marginal portion of a shoe upper to a last, a carrier adapted for movement inwardly and outwardly over a shoe bottom to wipe the upper toward lasted position, a tack holder movably mounted in said carrier, means for driving a tack from said holder, and means for driving the tack holder downwardly against the upper to flatten the stock adjacent to the tack. 80
47. In a machine for use in making shoes, the combination with a pounder, and means for actuating the pounder over the surface of the shoe bottom inwardly and outwardly from the edge of the shoe, of means for yieldingly actuating the pounder toward the surface of the work having provision for relieving the pressure of the pounder upon the work before its outward movement. 90
48. In a machine for use in making shoes, the combination with tack driving means, of a pounder, and means for actuating the pounder in a direction substantially perpendicular to the surface of the work in time relation with the tack driving operation. 100
49. A machine of the class described, having in combination means for securing an upper to an innersole, and automatically operating means for pounding the upper adjacent to the securing point in the same operation of the machine in which the fastening of the upper is effected, said machine having provision for imparting a yielding quality to the blows of the pounder. 105
50. A lasting machine having in combination means for working an upper over a last, means for securing the upper in overworked position, and automatic means including a yielding element for pounding the overworked portions of upper. 115
51. In a machine for working an upper over a last, means for crimping the upper, means including a yielding element for pounding the crimped portions of upper, and means for securing said portions of upper to an innersole. 120
52. In a machine of the class described, the combination with means for positioning a shoe, of pounding means constructed and arranged to act upon the shoe bottom from the edge thereof inwardly beyond the location for the lasting tacks, actuating mechanism 125
- 65 130

therefor, and means for inserting lasting tacks while the pounding operation is in progress.

53. In a machine for working an upper over a last, the combination with pincers, means for actuating the pincers to pull the upper, and means for actuating the pincers to crimp the upper, of means for pounding the crimped upper.

10 54. In a machine of the class described, the combination with a pounder and means in-

cluding a yielding element for actuating the pounder inwardly away from the edge of the innersole and downwardly toward the inner-sole, of operatively connected mechanism for 15 securing the upper to the innersole.

Signed by me at Lynn this 6 day of Mar.
A. D., 1899.
